UNITED STATES PATENT OFFICE

2,461,756

DISK PICTURE PROJECTOR

Ralph S. Moore, Visalia, Calif.

Application March 16, 1945, Serial No. 583,015

2 Claims. (Cl. 88—27)

1

The invention appertains to means for still picture projection, and has for one of its several objects to provide a means of arranging a sequence of still pictures, in either circular or spiral series, upon a transparent disc structure, for the projection of the pictures onto a viewing screen, in the order of the sequential arrangement thereof; the pictures being either photographed on a circular film to be incorporated in the disc structure, or to be separately photographed and mounted, either temporarily or permanently, on or in the disc structure; such picture discs having the advantages of being durable, easily handled, changed, and mailable, and not easily breakable, hence, capable of standing up over long periods of use, without loss of continuity because of broken film.

Another object of the invention has to do with the provision of a means especially designed to project the still pictures from the aforesaid disc structure, in the order of the sequential arrangement of the pictures, at a predetermined rate of speed; the machine being automatic in operation and provided with means for varying its speed to suit particular projection requirements.

With these and other objects and advantages in view, the invention resides in the certain new and useful combination, construction, and arrangement of parts, as will be hereinafter more fully described, set forth in the appended claims, and illustrated in the accompanying drawings, in which:

Figure 1 is a vertical, longitudinal section, through the picture projection apparatus, in accordance with the invention;

Figure 2 is a vertical, transverse section, taken through the line 2—2 on Figure 1, looking in the direction of the arrows;

Figure 3 is a face view of the master control disc and of the intermittent feed sprocket therefor, the spindle mounting for the control disc and the operating shaft for the feed sprocket being shown in cross section;

Figure 4 is an enlarged, fragmentary, vertical, transverse section, taken through the line 4—4 on Figure 1, looking in the direction of the arrows; and

Figure 5 is a rear face view of a picture disc in abutted, operative relation, with the rear face of a modified form of master control disc.

Referring to the drawings in detail, and more particularly to Figures 2 and 5, a picture record disc, in accordance with the invention, is made up of a transparent disc 10, which may be formed of glass or a plastic, having a series of related

2

pictures 12 affixed thereto, either temporarily or permanently, or it may take the form of a circular film or sensitized disc, having the pictures printed thereon and, in either case, the pictures are arranged in either a spiral sequence, as shown in Figure 2, or a circular sequence, as shown in Figure 5.

For the purpose of projecting the pictures from interchangeable record discs of this kind, onto a suitable viewing surface or screen (not shown), I have provided an automatic projector, which is comprised in a substantially rectangular cabinet, having a bottom wall 14, side walls 16, a rear wall 18, a front wall 20, and a top wall 22. Rising vertically within the cabinet, rearwardly of the transverse center thereof and centered between the side walls 16, is a supporting structure for the picture disc mounting and actuating mechanism, the same having a solid upper part 24 and spaced parallel lower parts 26; the latter acting as guides or rails for a slide member or carriage 28. Passing through the slide member 28, is a spindle 30, preferably in the form of a headed bolt, having its headed end spaced from the front side of the slide member and carrying a coiled spring 34, positioned thereon between a pair of washers 36 and 38, the washer 36 bearing against the bolt head and the washer 38 against the front face of the slide member, while its rearwardly directed end is screw threaded to receive a winged nut 32 and a washer 40.

Mounted on the spindle 30, immediately in rear of the slide member 28, is a rearwardly flanged hub 42, against the flanged end of which, a master control disc 46, of a transparent material, such as glass or the like, is abutted; the hub being secured on the spindle by means of a set screw 44, while the control disc is clamped between the hub and the washer 40, when the winged nut 32 is tightened. Prior to the engagement of the washer 40 and the winged nut 32 on the spindle 30, a picture record disc 10 is positioned on the latter, in abutted relation with the rear side of the control disc 46, and is clamped in that relation, when the washer 40 and the winged nut 32 are tightened in place on the spindle. To one side of the central opening to receive the spindle 30, the picture record disc 10 is provided with an aperture 10a, to be engaged on a guide pin 48, projecting rearwardly from the control disc, to the end that the first picture of a sequence on each record disc will always be at the starting point of rotation of the control disc.

55 The control disc 46, as shown in Figures 1

through 3, has its front side provided with a spiral flange 50, for use with a picture record disc 10 having the pictures 12 arranged thereon in a spiral sequence; the pictures registering with the space between the convolutions of the spiral flange, when the two discs are in assembly on the spindle 30. In the modified form of control and picture record disc assembly, as shown in Figure 5, wherein the pictures 12' are arranged in a circular sequence on the record disc 10', the control disc will have a circular flange 50', which will conform to the circle defined by the inner end edges of the several pictures, substantially as shown.

The picture record and control disc assembly is to be rotated by means of an intermittent sprocket 54, the teeth of which engage with apertures 52, formed in the flanges 50 or 50', as the case may be; the sprocket being keyed on the rear end of a shaft 56, that is journaled intermediate its ends in a bearing 58, mounted in the upper part 24, of the supporting structure 26. The forward end of the shaft 56 is supported in a bearing member 60 and carries a cam element 62, having high points spaced apart proportionately with respect to the width of the individual pictures on a picture record disc. The cam element 62 is disposed in the path of movement of a lug 64, mounted on the rear side of a grooved pulley 66, which is keyed on a shaft 68, journaled in the upper end of a bearing bracket 70, rising from the bottom wall 14, of the cabinet. Mounted within the lower part of the bracket 70, is the housing 78, of a reduction gearing (not shown), having a shaft 76 projecting from its forward side and carrying a smaller grooved pulley 74, that is connected by an endless belt 72 to the pulley 66. Projecting rearwardly from the housing 78, is a shaft section 80, which is coupled, as at 82, to the rotor shaft 84, of an electric motor M.

Formed in the front wall 20, of the cabinet, is an aperture 86 and, secured on the inner side of the wall, in line with the aperture, is a tubular member 88, in which a lens tube including an objective lens system 90 is slidably supported; a projecting lens 92 being mounted in the front end of the latter. For the purpose of adjusting the lens 92, relatively to the aperture 86, the tubular member 88 is provided with a longitudinally extending slot 94, in its lower side, and the lens tube 90, with a lug 96, depending through the slot. An adjusting screw 98 is mounted in the front wall 18, below the aperture 86 therein, and has its inner end in screw threaded engagement with an opening formed in the lug 96. A framing device 100 is carried at the rear end of the tubular member 88, if desired, in order to impart to the projected pictures the advantages obtaining from its use.

Formed in the upper part 24, of the supporting structure 26, is an aperture 102, which is disposed in line with projection aperture 86, in the front wall 18 of the cabinet, and also with a condenser lens 104, mounted in the vertical wall 108, of a lamp compartment 106, provided in the upper rear part of the cabinet; an electric lamp bulb 112 being supported on the bottom wall 110, of the compartment, and disposed in line with the condenser lens 104 and a reflector 114, mounted on the rear wall 14, of the cabinet, so that a beam of light from the lamp bulb 112 is projected by the condenser lens 104 through the path of movement of the pictures 12, on the record disc 10, when the latter and the control disc 46 are intermittently moved to bring the pictures success-

sively into registry with the aperture 102. In order to dissipate heat from within the lamp compartment 106 and from the picture record disc 10, a fan 116 is keyed on the rear end of the rotor shaft 84, of the motor M, within a housing 118, which is connected by a conduit 120 with the interior of the lamp compartment, through the bottom wall 110, and with the interior of the cabinet, as at 122, through the lower portion of the vertical wall 108, so as to discharge an air stream against and upwardly of the rear side of the picture record and control disc assembly; discharge openings for the air being provided in the top wall 22, of the cabinet, as at 124, which open into the latter at both sides of the vertical wall 108, of the lamp compartment.

Mounted on the pulley 66, and projecting from the edge thereof, is a shutter 126, which, in the rotation of the pulley, cuts the light beam in its passage from the aperture 102, to and through the framing device and projecting lens assembly. During the major period of rotation of the pulley 66, in each revolution thereof, each of the pictures 12, on the record disc 10, are projected onto the viewing surface or screen, while a change from one picture to another, in the sequence of the arrangement of the same on the record disc, is effected during each blackout period of the light beam, by the shutter 126. This operation is accomplished by the synchronized relationship established between the operative parts, the record and control disc assembly remaining stationary during the major period of rotation of the pulley 66, through each revolution thereof, and turning through a distance equal to the width of a single picture, on the record disc 10, when the intermittent sprocket 54 is likewise turned by the movement imparted to the cam 62, by the lug 64, on the inner side of the pulley 66, the motion of the cam being transmitted to the sprocket through the shaft 56. For the purposes of the instant invention, the cam 62 has been provided with four high points, so that it is given a quarter turn each time the lug 64 engages one of the high points, as a consequence of which, the shaft 56 and the sprocket 54 are likewise given a quarter turn, which distance of turn is equal to the width of a single picture 12. The number of pictures to be projected per minute is to be varied by a predetermined speed of rotation of the pulley 66 obtained from a regulation of the speed of operation of the motor M, which may be accomplished with any suitable means, e. g., a rheostat (not shown).

In the operation of the projector, as thus constructed and arranged, with a picture record disc 10 having the pictures 12 arranged thereon in a spiral sequence and a control disc 46 provided with a complementary spiral flange or track 50, the record and control disc assembly is to be removed from and replaced upon the spindle 30, by the removal and replacement of the winged nut 32 and the washer 44, when the slide member 28 is elevated on the guides or rails 26 to permit of the engagement of the teeth of the intermittent sprocket 54 with the first of the apertures 52 at the inner end of the flange or track; a sufficient clearance being provided at the upper ends of the guides or rails 26 to allow the slide member to be raised to a height that will permit the flange or track 50 to be positioned above the intermittent sprocket 54 and thereafter lowered to cause the teeth of the latter to engage with the apertures 52. With the rotation of the record and control disc assembly, the slide member 28 automati-

cally lowers correspondingly with the ravel of the flange or track 50 relatively to the sprocket 54; it being understood that the first picture 12, of a given sequence of the same, is positioned on a record disc 10, relatively to the inner starting end of the flange or track 50, on the control disc 48, and the proper relationship between the record disc and the control disc is accurately established by the engagement of the guide pin 48, on the rear side of the control disc, with the aperture 10a, in the record disc 10.

Without further description, it is thought to be obvious that I have provided an extremely simplified and inexpensive still picture record disc and projector system, of particular worth for general advertising purposes and the like, wherein the picture records can be manufactured, distributed, and/or sold, independently, such as phonograph records and the like, or they may be manufactured and sold in combination with the projector. The projector may be set so that it is automatic in operation for the projection of a given sequence of still pictures onto a viewing surface or screen.

Having thus fully described a preferred embodiment of my invention, it is to be understood that changes in design and in minor details of construction and arrangement of the parts thereof may be resorted to, provided such changes are within the limits defined by the scope of the appended claims.

What I claim is:

1. In a picture disc projector, the combination which comprises a projector housing having an intermediate partition, said partition having an opening and a light projecting aperture therein, a carriage slidably mounted in said partition opening for vertical movement therein, a picture disc having a series of pictures arranged arcuately on the face thereof, a transparent master disc for supporting said picture disc in face adjacency therewith, means for mounting said picture and master discs for unitary rotation on said carriage, said master disc having secured thereto an axially projecting arcuate flange conforming to the curvature of said arcuately arranged series of pictures and having a series of equally spaced apertures formed therein, a sprocket rotatably supported on said housing and having the teeth thereof arranged for coaction with said flange apertures, said sprocket being disposed beneath said flange in supporting relation thereto and arranged in predetermined spaced relation with respect to said light projecting aperture sufficient to position said series of pictures in registry therewith and to elevate said carriage in said partition variably in accordance with the curvature of the flange upon unitary rotation of said picture and master discs as the sprocket rotates, a light source associated with said light projecting aperture, a condenser lens positioned between said light source and said picture disc, an objective lens system mounted in said housing in alignment with said light source, condenser lens, and light projecting aperture, a shutter element rotatably supported on the housing between said objective lens system and said light projecting aperture and arranged to prevent passage of light from said light source through said objective lens during a fractional portion of one complete revolution of the shutter, means for rotating the shutter at a predetermined speed, and intermittent driving connections between said shutter rotating means and said sprocket for causing predetermined intermittent rotary motion of the sprocket effective to advance said series of pic-

tures successively into registry with said light projecting aperture during successive fractional movements of the shutter respectively.

2. In a picture disc projector, the combination which comprises a projector housing having an intermediate partition, said partition having a slide receiving opening and a light projecting aperture therein, a carriage slidably mounted in said partition for vertical movement within said slide receiving opening therein, a transversely disposed pin carried by said carriage for rotation thereon, means for frictionally limiting free rotation of said pin on the carriage, a picture disc having a series of pictures arranged spirally on the face thereof, a transparent master disc for detachably supporting said picture disc in face adjacency with one face thereof, means for detachably and frictionally locking said picture and master discs on said pin for unitary rotation therewith, a complementary spiral flange secured to the other side of said master disc and arranged thereon with said series of spirally arranged pictures in registry with the spaces between the convolutions of the spiral flange when the picture disc is supported on the master disc, said flange having a series of equally spaced openings formed thereon, a sprocket rotatably supported on the projector housing beneath said flange in supporting relation thereto and in predetermined spaced relation with respect to said light projecting aperture sufficient to bring said series of pictures into registry therewith, the teeth of said sprocket engaging said apertures in the flange whereby said carriage is elevated variably in accordance with the curvature of the spiral flange as the flange is moved over the sprocket upon rotation thereof, a light source associated with said light projecting aperture, a condenser lens interposed between said light source and said light projecting aperture in alignment therewith, an adjustable objective lens system supported on the projector housing in alignment with the light projecting aperture and said light source, a shutter element rotatably supported on the housing between said light projecting aperture and said objective lens system and arranged to prevent passage of light therethrough from the light source during a fractional portion of one complete revolution of the shutter, means for circulating cooling air for said light source, means for rotating said shutter element and said air circulating means at predetermined speeds, and intermittent driving connections between said shutter rotating means and said sprocket for causing predetermined intermittent rotary motion thereof effective to advance said series of pictures successively into registry with said light projecting aperture during successive fractional movements of the shutter respectively.
